US00D544485S

(12) **United States Design Patent** (10) Patent No.: **US D544,485 S**
Chen et al. (45) Date of Patent: **** Jun. 12, 2007**

(54) **HANDHELD COMPUTER**

(75) Inventors: **Chun-Hsien Chen**, Hsin-Tien (TW);
Ming-Che Chan, Hsin-Tien (TW)

(73) Assignee: **Unitech Electronics Co., Ltd.**, Taipei
(TW)

(**) Term: **14 Years**

(21) Appl. No.: **29/233,863**

(22) Filed: **Jul. 12, 2005**

(51) LOC (8) Cl. **14-02**

(52) U.S. Cl. **D14/428**

(58) Field of Classification Search **D14/420,**
D14/425, 426, 428, 429, 453, 346, 34; 358/473;
235/462.43, 462.45, 462.47, 462.48, 472.01,
235/472.02; 16/422, 110.1, 430, 431

See application file for complete search history.
